(57) **CLAIM**

I claim the ornamental design for a ring for a fighting sport, as shown and described.

DESCRIPTION

FIG. 1 is an isometric view of a first embodiment of a ring for a fighting sport, embodying my new design;

FIG. 2 is the left elevational view thereof, the right elevational view thereof being identical to the left elevational view thereof;

FIG. 3 is the front elevational view thereof, the rear elevational view thereof being identical to the front elevational view thereof;

FIG. 4 is a top plan view thereof, the bottom plan view thereof does not form any part of the claimed design;

FIG. 5 is an isometric view of a second embodiment of a ring for a fighting sport embodying my new design;

FIG. 6 is the left elevational view thereof, the right elevational view thereof being identical to the left elevational view thereof;

FIG. 7 is the front elevational view thereof, the rear elevational view thereof being identical to the front elevational view thereof; and,

FIG. 8 is a top plan view thereof; the bottom plan view thereof does not form any part of the claimed design.

The broken lines in the figure drawings represent unclaimed environment only and form no part of the claimed design.
